Primary Examiner — Cynthia Ramirez*(74) Attorney, Agent, or Firm* — Brinks Hofer Gilson & Lione(57) **CLAIM**

The ornamental design for a display support with an indicator window, as shown and described.

DESCRIPTION

FIG. 1 is a plan view of a display support with an indicator window; and,

FIG. 2 is a close up plan view of the indicator window shown in FIG. 1.

The broken lines showing various aspects of the display support shown in FIGS. 1 and 2 are for environmental purposes only and do not form any part of the claimed design.
